TIE BRACKET

Louis C. Piazza, Western Springs, Ill., assignor to
Soundex Corporation, Chicago, Ill., a corpora-
tion of Illinois

Continuation of application Serial No. 448,466,
April 30, 1930. This application October 26,
1931. Serial No. 571,047

6 Claims. (Cl. 72—103)

This application is a continuation of a pending application, Serial No. 448,466, filed April 30, 1930, and relates to tie brackets, more especially to such tie brackets as are particularly applicable to such tie brackets as are particularly applicable 5 for tying together two spaced wall parts that constitute a mold for a filler of concrete or the like.

I propose to make building walls of an outer section of stucco laid on metal lath, an inner 10 wall section of insulating slabs, and between the two a load sustaining filler of concrete or the like. The insulating slab section and the opposite metal lath section constitute a permanent form or mold for the concrete, and are tied together in spaced relationship by novel tie brackets which constitute the present invention.

It is one of the objects of the present invention to provide a simple and economical tie bracket which may be easily inserted in place 20 during the building of the wall. It is a further object of the present invention to provide a tie bracket which will serve to hold two adjacent insulating slabs together in addition to tying the two wall sections together. I accomplish this end 25 by providing a bracket having a horizontal portion extending between the two walls and provided with projections at its free end for embedding the same into the insulating building slabs. At its opposite end the horizontal portion 30 of the tie bracket is provided with a vertical portion which may be tied or otherwise secured to the wire lath.

I have discovered that there is another factor of considerable importance that must be taken 35 into consideration in the design of a tie bracket such as is here contemplated. Where a thin coating of plaster or the like is to be applied to one of the wall surfaces it is desirable that there be no contact or bond between the bracket and the plaster. This is important because should 40 there be rusting of the protruding end of the bracket that is in contact with the plaster the increase in volume of the metal, due to the rusting, may be sufficient to spall the plaster. I 45 overcome this objectionable feature by providing a bracket that does not protrude beyond the outer surface of the insulating slab. My tie bracket is secured to the insulating slab intermediate the ends thereof by the use of double 50 ended nails or by the provision of pointed projections formed integrally with the bracket and adapted to be embedded in the slabs.

The attainment of the above and further object of the present invention will be apparent 55 from the following specification taken in con-

junction with the accompanying drawing forming a part thereof.

In the drawing:

Figure 1 is a top plan view of a wall constructed in accordance with my invention, said view being 60 taken along the line 1—1 of Figure 2 and looking in the direction of the arrows;

Figure 2 is a transverse sectional view of the wall, said view being taken along the line 2—2 of Figure 1.

Figure 3 is a perspective view showing a pair of 65 clips such as may be used in the wall shown in Figure 1, and illustrating the manner in which the clips are secured together;

Figure 4 is a transverse sectional view taken 70 along the line 4—4 of Figure 3 and showing the manner in which the spacing clips are secured together;

Figure 5 is a view of the back of a modified 75 form of tie clip;

Figure 6 is a sectional view taken along the line 6—6 of Figure 5;

Figure 7 is a fragmentary perspective view of another form of clip;

Figure 8 is a side view of still another form of 80 clip;

Figure 9 is a perspective view of a pair of clips of a construction somewhat different from that shown in Figure 3; and

Figure 10 is a view of a double ended nail used 85 in connection with the clips of Figure 10.

Reference may now be had more particularly to Figures 1 and 2 showing a fragmentary portion of a wall constructed in accordance with the principles of my invention. In this embodiment 90 the wall comprises one portion indicated at 1 formed of insulating slabs, as shown at 2, 3 and 4. These slabs are generally rectangular and about 2" thick, the sides being about 16" by 48", although it is to be understood that the invention is not limited to the use of a slab of this size as the slab may be made of any size desired. The slabs are heat insulating and are preferably, although not necessarily, formed of long fibrous material, such as excelsior or the like, promiscuously intertwined and held together by a suitable binder. A method of making such slabs is shown in the pending application of Herbert Libberton, Serial No. 429,587, filed February 19, 1930, to

which reference may be had for a more complete 105 description of a method of making slabs such as are suitable for use in connection with a wall as shown in this application. The present invention is, however, not limited to the use of any particular kind of slab, nor is it limited to the 110

use of slabs made by a process such as is referred to in the above application. It is only essential that the slabs used shall have a surface texture of such a character as to cause it to adhere to 5 concrete rather than to part from it.

In the slab shown the fibers are loosely and promiscuously intertwined so that the surface of the slab has a large number of interstices into 10 which concrete or the like may enter. The slabs 2, 3, and 4 are built up to form a wall, said slabs being laid with the ends in adjacent rows staggered in the same manner that the bricks are laid. A metal lath 6 is mounted in spaced parallel relationship to the wall portion 1. The 15 metal lath 6 is held in position in spaced relationship to the wall portion 1 by means of tie clips or brackets 8 that are secured to the wall portion 1 and to the metal lath. The bracket shown may be L shaped and comprise a horizontal 20 portion 10 and a vertical portion 11. The tie clip or bracket may be of a construction such as is shown more particularly in Figures 3 to 7. The form of bracket shown in Figures 3 and 4 is an L shaped channel section and is formed of 25 metal. The flanges of the channel are cut away adjacent the end of the horizontal portion 10 as indicated at 15, and the end of the base portion is slit centrally for a short distance and the opposite end bent in opposite directions, as indicated 30 at 17 and 18. The ends 17 and 18 are pointed to facilitate their insertion into a slab in the same manner that a nail is inserted into a yielding object. The tie clips or brackets 8 may be arranged in vertical alignment with adjacent vertically aligned brackets secured together. This 35 is illustrated in Figure 3.

The flanges of the channel of the vertical portion 11 of the bracket are forced outward slightly, thus permitting the insertion of the base of another bracket into the same. This is illustrated 40 at Figures 3 and 4. The flanges of the two channels that have been inserted into one another are then bent inward, thus crimping the two together. In addition the portion 11 of the bracket has a 45 number of holes 20 formed therein in spaced relationship. The holes in the two brackets are brought together and then the brackets may be secured by means of a wire or the like. The distance from the ends 15 of the flanges to the 50 pointed portions 17 and 18 is equal to one-half of the thickness of an insulating slab, and the bracket is brought against the slab with the point 18 at the center of a slab. The point 18 is then forced into the slab with the point 17 extending upward. Another slab is then brought down 55 above the first slab and upon being forced downward the end 17 enters the center of the bottom portion of that slab. The portions 15 of the flanges bear against the inner sides of the slabs. The vertical portion 11 of the tie bracket is 60 secured to the metal lath 6 in any desired manner. The channel may be of such a small cross-sectional area as to permit insertion thereof through the openings in the metal lath, or if it is too large 65 to secure to the lath in that manner it may be tied to the lath by means of wires or the like.

The tie brackets effectively prevent bulging of the lath. Concrete or other self-setting plastic material may then be poured into the space between the wall portion 1 and the lath portion 6. These portions act as a form for the concrete and the concrete rigidly unites itself to the insulating slab because of the large number of small interstices in the slab. Likewise the concrete firmly 75 embeds itself in the metal lath due to the large

number of small openings in the lath. It is to be noted that the bracket ties do not come into contact with the facing materials that may be placed on the outer side of the wall 1, but are driven into the center of the slab. This effectively prevents any possibility of condensation at the end of the tie bracket.

Reference may now be had to Figures 5 and 6 showing a portion of a modified form of bracket which in general is similar to that shown in Figure 3. The bracket is channel shaped, as shown in Figure 3, and at its back portion 11 has a number of stamping or punchings 25 formed therein. These permit the ready securing of the tie bracket to the metal lath since the expanded portions 25 may be forced into adjacent openings in the lath and then upon moving the bracket downward it becomes rigidly secured to the lath. In other detail this bracket may be the same as that shown in Figures 3 and 4.

Figure 7 shows still another form of a bracket which is of small L shaped cross-section. Otherwise this bracket is essentially similar to that shown in Figures 3 and 4. This bracket has a number of holes 28 formed at the corner of its vertical portion 11 for facilitating the securing of adjacent brackets together. These holes correspond in function to the holes 20 of Figure 3. The base portion 10 of this bracket has a downwardly formed stamping 30 formed therein and an upwardly formed stamping 31 also formed therein. At the end of the bracket is formed a nail hole 32. The distance between the center of the nail hole and the portion 30 is equal to about one-half of the thickness of an insulating slab. When this bracket is used the portion 35 is rested upon the top part of an insulating slab with the portion 30 thereof resting against the side of the slab. A nail may then be driven through the hole 32 to rigidly secure the bracket 115 to the top of the slab. The upper end of portion 31 is pointed in order to enable the same to readily embed itself in an insulating slab that is mounted on top of the slab whereon the bracket rests. It is to be noted that the end of the L shaped bracket is flattened in order to provide a greater surface area for the portion 30 and the portion 31.

If desired the bracket may be made as shown in Figure 8. This bracket is U shaped rather than L shaped. It may be of channel cross-section or of an L shaped cross-section, as shown in Figure 3 or in Figure 7. In this form of bracket the base portions 40 and 41 are spaced apart by a vertical portion 42 which is of a height exactly equal to the height of one of the insulating slabs, and the prong 45 extends into the bottom of one of the slabs and the prong 46 extends into the top of that same slab. In addition this clip is provided with a lower prong 48 which extends into the slab below that into which the prong 45 is embedded and the clip is provided with a prong 49 that extends into the slab above that into which the prong 46 is inserted. In other detail this bracket may be the same as that shown in any of the other Figures. When a bracket, such as is shown in Figure 8, is used then the brackets are not mounted in vertical alignment but rather they are staggered and therefore it is not necessary to secure 145 together two vertically spaced brackets.

Stucco, brick veneer, stone, or other material may be applied to the outer side of the wall in order to improve its appearance. Likewise plaster or the like may be applied to the inner side of 150

the wall. This is indicated, in connection with the metal lath 6, at 50.

In Figure 9 there is shown still another form of wall tie bracket which may be used in a wall construction such as is shown in Figures 1 and 2. This bracket is formed of a bar of metal having a generally V-shaped cross-section and bent into an L shape. The vertical leg 60 of the bracket is secured to the metal lath in any preferred manner. For instance, it may be tied thereto at a plurality of spaced points along its length by means of tie wires. The horizontal leg 61 extends from the metal lath to the insulating slab and is flexed at the end as indicated at 62. The flexed end is provided with one or more spaced holes as indicated at 63 and 64 to facilitate the securing of the bracket to the insulating slab. The flexed end 62 of the bracket is placed between two adjacent slabs of insulating material in the manner shown in Figure 2 and is secured to both of the slabs by means of a double ended nail such as is shown in Figure 10. The flat end 62 is placed on top of one slab and the long end 66 of the nail shown in Figure 10 is driven through the opening 63 in the tie bracket until the flat portion 67 of the nail abuts against the tie bracket. The short end 68 of the nail projects upward from the flattened portion 62 of the bracket and a second insulating slab may be brought down on top of the first one, said portion 68 of the nail entering into the upper slab and thereby securing the two slabs together. Where two nails are used the second nail may, if desired, be reversed so that its short end 68 extends downwardly and its long end 66 extends upwardly. This, of course, is optional. This form of tie bracket is preferable to the brackets previously described in that it is cheaper to make and the amount of labor involved in setting the same up on the job is also less than that involved in connection with the use of the other bracket here shown.

In compliance with the requirements of the patent statutes we have herein shown and described a few preferred embodiments of our invention. It is however, to be understood that the invention is not limited to the precise construction herein set forth, the same being merely illustrative. What I consider new and desire to secure by Letters Patent is:

1. Means for uniting inner and outer wall members of a single wall, said means comprising a metal bracket of a channel shaped cross section having a horizontal portion including means adjacent the free end adapted to be inserted into a wall member and at its opposite end a vertically extending portion adapted to be secured to the opposite wall member to secure the members together, said vertical channel portion being deformed at its outer end to permit the nesting therewith of the opposite end of an adjacent and similar bracket.

65

70

75

2. A tie bracket comprising a metal member having a vertical portion adapted to be secured to a wall section and a horizontal portion adapted to be secured to another wall section to secure the two sections together in spaced relationship, the bracket being of a generally L shaped cross section whereby the free end of the vertical section may have nested therein the opposite end of the vertical section of another bracket, the free end of the horizontal portion being flat to facilitate placement thereof within a wall.

3. A tie bracket including two spaced horizontal portions joined by a vertical portion, the free ends of the horizontal portions being adapted to enter between adjacent slabs of a wall, means adjacent the free ends for limiting the extent to which the ends may extend into the wall, and oppositely directed double pointed means for securing the free ends of the tie bracket in place within a wall section.

4. Means for uniting inner and outer wall members of a single wall, said means comprising a metal bracket having a horizontal portion of channel-shaped cross section and a vertically extending portion, the flanges of said channel-shaped horizontal portion stopping short of the free end thereof to provide means adapted to be inserted into a wall member, the extent of the insertion being limited by said flanges, said vertically extending portion being adapted to be secured to the opposite wall member to secure the members together.

5. Means for uniting inner and outer wall members of a single wall, said means comprising a metal bracket of a channel-shaped cross section having a horizontal portion, the web of said horizontal portion extending beyond the flanges thereof to provide means adjacent the free end adapted to be inserted into a wall member and at its opposite end a vertically extending portion adapted to be secured to the opposite wall member to secure the members together, said vertical channel portion being deformed at its outer end to permit the nesting therewith of the opposite end of an adjacent and similar bracket.

6. Means for uniting inner and outer wall members of a single wall, said means comprising a flanged metal bracket having a horizontal portion and a vertically extending portion, said horizontal portion extending forward of the flanges thereof to provide means adjacent the free end thereof adapted to be inserted into a wall member with said flanges in abutting engagement with said member, said vertically extending portion adapted to be secured to the opposite wall member to secure the members together.
